UNITED STATES PATENT OFFICE.

CHRISTIAN Z. F. ROTT, OF PITTSBURG, PENNSYLVANIA.

APPARATUS FOR FINISHING ARTICLES OF GLASSWARE.

SPECIFICATION forming part of Letters Patent No. 625,468, dated May 23, 1899.

Application filed June 18, 1898. Serial No. 683,798. (No model.)

To all whom it may concern:

Be it known that I, CHRISTIAN Z. F. ROTT, a resident of Pittsburgh, in the county of Allegheny and State of Pennsylvania, have invented a new and useful Improvement in Apparatus for Finishing Articles of Glassware; and I do hereby declare the following to be a full, clear, and exact description thereof.

My invention relates to apparatus for fire-polishing articles of glassware.

The object of my invention is to provide a simple form of apparatus of this character which will convey the articles of glassware fed thereto to the proper position with reference to the heating-furnace and there manipulate said article in such a manner as to fire-polish it thoroughly and convey it away without the employment of any labor other than that required to feed and operate the machine.

To these ends my invention comprises the novel construction set forth in the specification and claims which follow.

To enable others skilled in the art to make and use my invention, I will describe the same more fully, referring to the accompanying drawings, in which—

Figure 1 is an end view in elevation of my improved apparatus. Fig. 2 is a vertical cross-section on line 2 2, Fig. 1. Fig. 3 is a plan view. Fig. 4 is a diagrammatic view of the movements of the transferring mechanism. Fig. 5 is an enlarged detail view of the supporting-rollers and mechanism for adjusting the same. Fig. 6 is a modified form of supporting-rollers.

Like letters indicate like parts in each of the figures.

The letter A designates a suitable frame for supporting the apparatus. Extending out from the frame A is the bracket a, in which is journaled the shaft a'. Secured to the outer end of the shaft a' is the hand-wheel a², by means of which said shaft is revolved. This shaft a' may, however, be operated by other than hand-power. A sprocket-wheel b is mounted on the inner end of the shaft a', and a sprocket-chain b' connects said wheel with the sprocket-wheel b² on the shaft b³ in the hanger A', depending from the frame A. A gear-wheel c on the shaft b³ meshes with

the pinions c' c² on the shafts c³ c⁴, respectively, journaled in the hanger A'.

Secured to the ends of the shafts c³ c⁴ are the cranks d d', respectively. The crankpins d² connect said cranks with the rods e e'. The upper ends of the rods e e' have the arms e² e³, extending in opposite directions, said arms having the forks f f' or other lifting means. Secured to the shaft c³ is the eccentric weight.

Mounted on the frame A are the guide-boxes h h', which act as supports and guides for the shanks i² of the bifurcated bearings i i'. Mounted on shafts k in said bearings i i' are the supporting-rollers l l'. These rollers may vary in shape and size according to the shape of the articles they are to support. Adjusting-screws m pass up through threaded openings in the angles m' on the frame, and said screws are adapted to engage the shanks i², whereby the bearings i i' may be raised or lowered, as desired.

In order to provide for the turning of the shanks i² and the adjustment of the rollers at different angles with reference to each other, I provide the adjusting-screw n, which passes through the swivels n', supported by the lugs n² on the bearings i i'. The screw n is contracted at about its mid-point, as at n³, said contracted portion bearing against a lug o. The screw n has right and left hand threads thereon. It is apparent from the above that by turning the screw n the rollers l may be moved away from each other and the rollers l' brought correspondingly nearer, or vice versa, according to the size and shape of the article to be supported thereon.

Beyond the rollers l l' are the receiving-rollers r r', the rollers r, together with the adjacent rollers l l', acting as a support for the article when it is first received in the apparatus and the rollers r' acting to receive it as it passes beyond the furnace.

Extending out from the frame A is the bracket s, within which is journaled the power-driven pulley s'. An endless belt s² passes from the pulley s' up under the pulley s³, up over the pulley s⁴, thence down under pulley s⁵, up over pulley s⁶, and down under pulley s⁷ to the pulley s'. Through power imparted

in this manner the rollers l l' are made to revolve in the same direction.

Supported on tracks t on the frame A are the furnaces t' , said furnaces being of any suitable construction, with refractory lining, and having the "glory-holes" t^2 facing each other. The furnaces are mounted on the wheels t^3 , which ride on the track t . Gas-supply pipes u enter the furnaces from below and furnish fuel thereto. Gas is admitted to said pipes by the openings u' , said openings being connected up by flexible pipe with the main supply. The glory-holes t^2 are preferably contracted in the form of segmental slots, as shown, and project up at a slight angle in order to direct the heat more effectually onto the object to be fire-polished. Furthermore, a recess or depression t^4 is formed in the face of the furnace, which forms a kind of pocket to retain the heat around the object.

To provide for the movement of the furnaces over the tracks toward and from each other, the treadles or foot-levers w are provided. The foot-levers are connected by the links w' with the levers w^2 , pivoted in the hangers w^3 . Secured to the levers w^2 are the arms x , which carry at their upper ends the hooks x' . These hooks x' engage with openings in the rings x^2 , surrounding the pipes u . It is apparent from the above that by depressing the foot-levers w the furnaces will move away from each other and that by raising said foot-levers they will approach each other for the purposes more fully hereinafter set forth.

35 I will now describe my improved apparatus as applied to the fire-polishing of lamp-chimneys, although its use may be extended to all other articles of glassware to which it may be found applicable.

40 The lamp-chimney y to be fire-polished is placed upon the receiving-rollers r , the rollers l l' having been previously adjusted by the adjusting-screws m n to correspond to the shape and size of said chimney. The distance between the furnaces t' is also previously arranged by means of the foot-levers w , so as to bring the ends of said chimney in proper proximity to the glory-holes to give the requisite fire-polishing effect thereto. The operator then grasps the hand-wheel a^2 and proceeds to rotate same. This rotation of the said wheel through the gearing mechanism operated thereby will cause the rods e e' to rise. The arms e^2 thereof ascending in line with the ends of the chimney y will, through the forks f , lift the chimney from the rollers. These forks then support the chimney at its base and neck. As the hand-wheel continues to revolve the rods e e' , as shown in the dia-grammatic view Fig. 4, ascend slightly farther, moving over toward the rollers l l' at the same time. When the highest point has been reached, said rods begin to descend in the same manner, moving toward the rollers l l' , until 60 they deposit the chimney between the said rollers, so that it is supported thereon. The rods

then descend out of the way. The chimney is now supported on the revolving rollers l l' , with its ends in close proximity to the glory-holes. The segmental slots t^2 , which form the glory-holes, direct the heat radially, and the ends of the chimney being on substantially the same curve a greater portion of the same is subjected to the heat, while at the same time the depressions t^4 tend to form pockets for the heat and less heat is wasted. After the chimney has been allowed to revolve in this manner the requisite time to remove any unevenness or roughness on its ends and has been properly fire-polished the operator again turns the hand-wheel a^2 , when the rods e e' follow the same course as before, the arms e^2 moving so as to bring their forks up under the chimney y to lift it from the rollers and deposit it on the receiving-rollers r' . The arms e^2 by the same movement have lifted a second chimney from the roller r and placed it on the revolving rollers l l' in the same manner as before. In this manner the machine is kept operating continuously, so that each time a chimney is removed from the revolving rollers another takes its place.

The construction shown and described may be modified and varied without departing from the spirit of my invention.

What I claim as my invention, and desire to secure by Letters Patent, is—

1. In apparatus for fire-polishing glassware, the combination with a suitable frame, of a support for the article of glassware in proper position with reference to the furnace, and mechanism for conveying said article to said support and lifting it up therefrom, substantially as set forth.

2. In apparatus for fire-polishing glassware, the combination with a suitable frame, of a support for the article of glassware in proper position with reference to the furnace, means for imparting a rotary movement to said article, and mechanism for conveying said article to said support and lifting it up therefrom, substantially as set forth.

3. In apparatus for fire-polishing glassware, the combination with a suitable frame, of revolving rollers adapted to support the article of glassware in proper position with reference to the furnace, and mechanism for conveying said article to said rollers and lifting it therefrom, substantially as set forth.

4. In apparatus for fire-polishing glassware, the combination with a suitable frame, of shafts supported thereon, revolving rollers mounted at each end of said shafts adapted to support the article of glassware in proper position with reference to the furnace, and means for changing the angle of said shafts with reference to each other, substantially as set forth.

5. In apparatus for fire-polishing glassware, the combination with a suitable frame, of shafts supported thereon, revolving rollers mounted at each end of said shafts adapted

to support the article of glassware in proper position with reference to the furnace, upright bearings on which said shafts are supported, and means for turning said bearings, substantially as set forth.

5 6. In apparatus for fire-polishing glassware, the combination with a suitable frame, of upright bearings on said frame, shafts fitting in said bearings, revolving rollers at each end 10 of said shafts adapted to support the article of glassware in proper position with reference to the furnace, the lower end of said upright bearings fitting in suitable seats and adapted to turn therein, and a right and left 15 hand screw engaging threaded openings in one of the ends of each of said upright bearings, substantially as set forth.

7. In apparatus for fire-polishing glassware, the combination with a suitable frame, of revolving rollers adapted to support the article 20 of glassware in proper position with reference to the furnace, upright bearings on which said rollers are supported, the lower ends of said bearings fitting in suitable seats and 25 adapted to turn therein, swivels having threaded openings on said bearings, and a right and left hand screw engaging the openings in said swivels, substantially as set forth.

8. In apparatus for fire-polishing glassware, the combination with a suitable frame, of a 30 support for the article of glassware exterior to and in proper position with reference to the furnace-opening, vertically-reciprocating lifting device adapted to convey the article to 35 said support and lift it therefrom, and mechanism for operating said lifting device, substantially as set forth.

9. In apparatus for fire-polishing glassware, the combination with a suitable frame, of a 40 support for the article of glassware exterior to and in proper position with reference to the furnace-opening, vertical rods having lifting arms, cranks connected to said rods, and connections between said cranks and a power- 45 shaft, substantially as set forth.

10. In apparatus for fire-polishing glassware, the combination with a suitable frame, of a support for the article of glassware exterior to and in proper position with reference 50 to the furnace-opening, a support on each side of said first support, vertical rods having lift-

ing-arms extending from opposite sides thereof, cranks connected to said rods, and connections between said cranks and a power-shaft, substantially as set forth.

55

11. In apparatus for fire-polishing glassware, the combination with a suitable frame, of a support for the article of glassware in proper position with reference to the furnace, rods having lifting-arms, cranks connected to 60 said arms, pinions on the crank-shafts, a gear-wheel meshing therewith, and means for rotating said gear-wheel, substantially as set forth.

12. In apparatus for fire-polishing glassware, the combination with a suitable frame, of a movable furnace, a support for the article of glassware in proper position with reference to said furnace, and mechanism for moving said furnace to and from said support, substantially as set forth.

13. In apparatus for fire-polishing glassware, the combination with a suitable frame, of a furnace, wheels supporting said furnace, a support for the article of glassware in proper 75 position with reference to said furnace, and mechanism for moving said furnace to and from said support, substantially as set forth.

14. In apparatus for fire-polishing glassware, the combination with a suitable frame, of a movable furnace, a support for the article of glassware in proper position with reference to the furnace, a lever, and connections between said lever and furnace for moving same to and from said support, substantially as set forth.

15. In apparatus for fire-polishing glassware, the combination with a suitable frame, of a movable furnace, a support for the article of glassware in proper position with reference to the furnace, a gas-supply pipe entering said furnace, a lever, and connections between said lever and said pipe for moving said furnace to and from the support, substantially as set forth.

95

In testimony whereof I, the said CHRISTIAN Z. F. ROTT, have hereunto set my hand.
